UNITED STATES PATENT OFFICE.

CHARLES J. HOLUB, OF NEWPORT, KENTUCKY, ASSIGNOR TO THE PECK-WILLIAMSON COMPANY, OF CINCINNATI, OHIO, A CORPORATION OF OHIO.

PIPE-FORMING MACHINE.

1,160,606.

Specification of Letters Patent. Patented Nov. 16, 1915.

Application filed February 12, 1912. Serial No. 677,155.

To all whom it may concern:

Be it known that I, CHARLES J. HOLUB, a citizen of the United States, residing at Newport, in the county of Campbell and 5 State of Kentucky, have invented certain new and useful Improvements in Pipe-Forming Machines, of which the following is a specification.

This invention relates to machines for 10 crimping the seams in uniting pipe sections and it deals more particularly with improvements adapting such machines for successively joining a plurality of sections to form lengths of piping, such for example as that 15 commonly employed for carrying hot air from furnaces.

One object within the contemplation of this invention is to render available a simple and inexpensive power press providing instrumentalities for simultaneously crimping the entire periphery of the seam between sections of piping of a rectangular or other shaped cross-section.

Another object is to provide a mechanism 25 of the foregoing nature in which the said instrumentalities may readily comprise interchangeable elements of various dimensions so that different sizes of pipe sections may be crimped as aforesaid.

Another object is to provide a mechanism 30 as aforesaid such that piping in considerable lengths and composed of a plurality of sections may without difficulty be formed by successive operations.

Other objects will be in part pointed out 35 or indicated in the following description and in part rendered obvious by means of the annexed drawings.

To render this invention more completely 40 comprehensible to those skilled in the art, drawings depicting one of the many possible embodiments thereof have been appended as a part of this disclosure and in such drawings like characters of reference 45 denote corresponding parts throughout all the views of which:—

Figure 1 is a front elevation of a press 50 illustrative of this invention, showing a rectangular center form or core, together with the top, bottom and side elements which function to simultaneously crimp the four sides of the seam between the pipe sections.

Fig. 2 is a section taken through line $x-x$ of Fig. 1, showing the mounting of the 55 center form or core partly in section and

partly in elevation. Fig. 3 typifies a seam between two sections of piping before being crimped into permanent form, and Fig. 4 indicates a similar seam after being crimped in this machine.

Continuing now by way of a more detailed description, it may be noted preliminarily that in order to enable the crimping surfaces of the dies to be formed as simply as possible, *i. e.* with plane faces, the preferred embodiment of this invention, as shown, is designed for use in connection with the form of seam indicated by Figs. 3 and 4.

At one end, the pipe section 1 is provided with an upturned flange 4 continuing into a downwardly turned shorter flange 5. The adjacent end of the companion pipe section 2 is provided with an upturned straight flange 6, which is inserted in the groove formed by the flanges 4 and 5, the parts being proportioned and arranged very much as indicated by Fig. 3. By reason of the template of which the pipe sections may be formed, sufficient flexibility exists to permit of this interfitting the same, manually. It 70 has been discovered that if some plane-faced pressure element be brought to bear against the apex of this seam, that by a straight-line depression, such seam will invariably turn 75 into the position indicated by Fig. 4 in 80 which the section 2 is securely crimped to the section 3.

To effect this operation rapidly and perfectly, this invention proposes a press arrangement somewhat of the character shown 90 in the drawings, in which A indicates a main frame in which is journaled the shaft 7 of the driving mechanism, which may, of course, assume any desirable form. On this shaft is mounted a suitable eccentric 8, 95 which operates the pitman 9, which in turn through the adjustable connection 10, operates the plunger or stamp 11. On the underface of the latter is detachably affixed a die plate 12, which in length corresponds 100 with the width of the pipe section to be crimped and constitutes a crimping die. The face 13, of the table 14, constitutes an anvil or complementary die for crimping the under-seam joining the pipe sections 105 whenever the head 11 is sufficiently depressed. To effect a simultaneous crimping of the right and left hand side-seams of the pipe sections, this invention proposes two die blocks 15 and 16, each of which is pref- 110

erably detachably affixed to similar members 17 which are supported on the table and which are arranged to move laterally in slides 18, being normally urged outwardly by springs 19, secured in suitable brackets. 5 To effect a translation of such slides, the plunger is provided with cams 20, which operate on the cam faces 21. By means of bolts 22, the cams 20 may be adjusted so as 10 to properly time the operations of the slides 21, so that all the crimping dies may simultaneously close in on the four sides of the pipe seams. By means of the adjustable connection 10 of the plunger the limit of co-operative engagement of all the dies relative 15 to the core block and anvil is changed but by adjusting the cams 20 only the limit of co-operative engagement of the side dies is changed relative to each other and to the 20 core block.

The core or center piece is indicated by 23 and preferably carries a sleeve-like guide 24 upon which the attendant may place the successive pipe sections to insure that they 25 may be held accurately in alinement with the companion section during the crimping operation. This core 23 may be provided with suitable means, such as the stem 25, whereby it may be detachably mounted in 30 the socket 26, whereby it may be carried at the end of the elongated member 27 which is preferably in the form of a tube to reduce weight. The core 23 is thus interchangeable with other cores adapted for 35 various shapes and dimensions of the piping. The elongated support 27 is flexibly supported, as by a pivot at a point 28, provided by the standard 29, remote from the crimping elements and the weight of the 40 parts may be balanced by a suitable spring 30. By this arrangement, it is possible to crimp into a single substantially integral length of say ten feet a plurality of pipe sections 1, 2, 3, etc.

45 It will thus be perceived that this invention is well adapted to achieve the objects and ends above stated and is characterized by great simplicity and convenience in manipulation.

50 Having described my invention, I claim:

1. A mechanism of the nature disclosed combining an anvil die, a die positioned opposite and movable toward said anvil die, 55 a floating core block interposed between said dies, a pipe guide carried by the core block and terminating with a contracted nose, side dies movable transversely to said second mentioned die and adapted to coact 60 with the sides of said block, and means for determining the limits of co-operation between the opposing members.

2. A mechanism of the nature disclosed 65 combining an anvil die, a floating core block arranged adjacent said die, and adapted to

be circumscribed by a blank to be compressed, a counterbalanced pivoted arm supporting said block, a pipe guide carried by the core block and terminating with a contracted nose, and a die positioned opposite 70 said core block and adapted to advance to move the same toward said anvil die to compress the blank carried thereby.

3. A mechanism of the nature disclosed combining a plurality of crimping dies, an 75 elongated supporting arm pivotally supported at a point remote from said dies, a core block carried at the end of said arm, a pipe guide carried by the core block and terminating with a contracted nose, means for 80 closing in each of said dies onto said core block, and means for determining the limits of co-operation between the dies and core block.

4. A mechanism of the nature disclosed 85 combining a plurality of crimping dies, an elongated arm supported at a point remote from said dies and adapted to move therewith at its free end, a core block carried by said free end, a pipe guide carried by the 90 core block and terminating with a contracted nose, means for simultaneously closing in said die on said core block, and means for determining the limits of co-operation between the dies and core block. 95

5. A machine of the nature disclosed combining an anvil, a floating core block, a pipe guide carried by the core block and terminating with a contracted nose, a plunger adapted to engage with the core block and 100 move it into co-operation with the anvil, members slidably mounted on opposite sides of the anvil, side dies detachably secured to said members, and means carried by the plunger adapted to simultaneously translate 105 the members to bring said side dies into co-operation with the core block.

6. A machine of the nature disclosed combining a vertically movable plunger, a movable die, a movable core block below said die, 110 an anvil below the core block, a pipe guide carried by the core block and terminating with a contracted nose, laterally movable opposing side dies, said plunger being adapted to translate the dies and core block to bring 115 said elements and anvil into co-operation.

7. A machine of the nature disclosed combining a vertically movable plunger, a movable die, a movable core block below said die, 120 a pipe guide carried by the core block and terminating with a contracted nose, an anvil below the core block, laterally movable opposing side dies, said plunger being adapted to translate the dies and core block to bring said elements and anvil into co-operation, 125 and means for determining the limits of co-operation between the plunger and anvil.

8. A machine of the nature disclosed combining a vertically movable plunger, a mov- 130

- able die, a movable core block below said die, a pipe guide carried by the core block and terminating with a contracted nose, an anvil below the core block, laterally movable opposing side dies, said plunger being adapted to translate the dies and core block to bring said elements and anvil into coöperation, means for determining the limits of coöperation between the plunger and anvil, and 10 means for determining the limits of coöperation between the side dies and core block.
9. A machine of the nature disclosed combining a base, a floating core block adapted to be moved into engagement therewith, a pipe guide carried by the core block and terminating with a contracted nose, a plunger movable to engage with the core block, opposing side dies slidably mounted on the base, cam members carried by the plunger 20 adapted to translate the side dies and means for adjusting said cam members to change the limits of coöperation of the side dies relative to the core block.
10. A machine of the nature disclosed combining a plurality of crimping dies, a core block, a pipe guide carried by the core block and terminating with a contracted

nose, means for simultaneously advancing said dies toward the core block, and means for determining the limits of coöperation 30 between said dies and core block.

11. A machine of the nature disclosed combining a plurality of crimping dies, a floating core block, a pipe guide carried by the core block and terminating with a contracted nose, means for simultaneously closing in said dies on said core block and means for determining the limits of coöperation 35 between said dies and core block.

12. A machine of the nature disclosed combining a plurality of crimping dies, a pivotally mounted supporting arm, a core block detachably secured thereto, a pipe guide carried by the core block and terminating with a contracted nose, a work support 40 secured to said core block, and means for simultaneously closing in said dies on 45 said core block.

In testimony whereof, I have hereunto set my hand.

CHARLES J. HOLUB.
